UNITED STATES PATENT OFFICE.

PERCY WARREN NOBLE, OF PONTIAC, MICHIGAN.

INTERNAL-COMBUSTION ENGINE.

1,104,442.

Specification of Letters Patent. Patented July 21, 1914.

Application filed January 27, 1913. Serial No. 744,303.

To all whom it may concern:

Be it known that I, PERCY WARREN NOBLE, subject of King George V of Great Britain, residing at Pontiac, in the county of Oakland and State of Michigan, have invented a certain new and useful Improvement in Internal-Combustion Engines, of which the following is a full, clear, concise, and exact description, reference being had 10 to the accompanying drawings, forming a part of this specification.

My invention relates to internal combustion engines and is of particular service in connection with four cycle internal combustion engines, though the invention is not to be limited to the denomination of the engine cycle.

The invention particularly relates to those engines employing piston cylinders in which 20 the engine pistons directly work and rotating valving cylinders surrounding the aforesaid cylinders. By means of my invention the working cylinder of the engine is maintained in fixed alinement. I also provide 25 means for lubricating the valving cylinder operating gearing.

The invention will be more fully described in connection with the accompanying drawings in which—

30 Figure 1 is a sectional view of one end of an engine structure constructed in accordance with the invention, the engine structure being shown in association with a tank for holding cooling fluid; Figs. 2 to 6 inclusive 35 are diagrammatic views collectively illustrating one-half of the valving cycle and one complete engine cycle, the upper portion of Fig. 2 also constituting a sectional view on line 2-2 of Fig. 1, some of the structural characteristics illustrated at the upper end of Fig. 2 being omitted in Figs. 3 to 6, inclusive.

Like parts are indicated by similar characters of reference throughout the different 45 figures.

The engine shown is a vertical engine, though obviously the invention is not to be limited to such a type. The engine casing 1 which underlies the engine cylinder is of 50 any suitable construction and supports, in any suitable manner, the engine shaft 2 diagrammatically illustrated in Figs. 2 to 6, inclusive, this engine shaft carrying the

usual crank 3 which is connected with the lower end of a connecting rod 4, the upper 55 end of this connecting rod being connected at 5 with a piston 6 in any usual or preferred manner. The piston 6 reciprocates within a stationary cylinder having two coaxial cylindrical walls 7, 8 between which 60 spacing 9 intervenes. The cylinder is also provided with two additional cylindrical walls 10, 11 between which spacing 12 intervenes, the walls 10 and 11 being also concentric with the walls 7 and 8. Spacing 65 12 also intervenes between the cylinder walls 8 and 10 in which a cylindrical sleeve 13 is received and in which spacing the sleeve 13 is adapted to be turned by means of any suitable gearing such, for example, as a spur 70 gear 14 surrounding and rigid with respect to the lower end of the sleeve 13 and a spur pinion 15 in mesh with the gear 14. The spacings 9 and 12 are in communication at the upper end of the cylinder by means of 75 one or more passages 16. A tank 17 which holds suitable cooling fluid such as water has piping connections 18 with the spacings 9 and 12 whereby the cooling fluid is automatically circulated. The cylinder has one 80 intake port 19 and one exhaust port 20 so spaced with regard to diametrically disposed openings 21 and 22 in the sleeve 13 that the functions of the cycle are correctly 85 carried out in any predetermined relation that may be desired. In the embodiment of the invention illustrated the pinion 15 operates at engine speed, the speed of the engine crank shaft, and the cylindrical sleeve 13 operates at one-quarter of the engine-speed. The ports 21, 22 in the sleeve 13 function alternately, that is, the port 21 will 90 function during one complete engine cycle in which cycle the port 22 will not function and the port 22 will function in the next cycle, in which latter engine cycle the port 21 will not function. In Fig. 2 the port 21 is on the point of being opened to admit explosive gas to the engine cylinder. In Fig. 3 the intake by way of the port 21 has just 100 about been closed. In Fig. 4 the engine has reached its firing point. In Fig. 5 the port 21 is just about to establish the exhaust passage from the cylinder. In Fig. 6 the exhaust stroke has been partially completed, 105 one engine cycle being then complete. In

the next engine cycle the port 22 performs the functions just described in connection with the port 21, the port 21 then being inactive. The port 21 and the port 22 are diametrically opposite so as to secure balancing action upon the sleeve 13. The port (21 or 22) which has completed its cycle of functions remains idle during the time its companion (22 or 21) is completing its cycle of functions so that the port which is inactive has opportunity in which to be cooled and when first brought into its functioning relation it is still further cooled by the incoming gas. By means of the construction 10 closed, a wide space intervenes between the intake and exhaust passages 23 and 24 leading through the walls 10 and 11 of the cylinder thus permitting ample sealing space between these passages 23 and 24 whereby 20 leakage between the passages 23 and 24 is readily prevented. While the ports 21 and 22 that thus function alternately are disposed in a rotating valve cylinder surrounding the working cylinder, I do not wish to 25 be limited, in all embodiments of the invention, to the presence of these ports in such a rotating cylinder.

Referring again more particularly to Fig. 1, it will be observed that the various walls 30 7, 8, 10 and 11 are maintained in fixed co-axial relation by the end walls 25, 26, 27 and 28 so that the space in which the cylindrical sleeve 13 turns is maintained fixed whereby said sleeve 13 may freely turn within its 35 space and at the same time maintain the desired intimacy of its contact with the walls 8 and 10. The lower end wall 28 is located below the valving cylinder 13 and engages the outer cylindrical wall 8 of the stationary 40 working cylinder so as to maintain the working cylinder in fixed alignment whereby the valving cylinder is not subject to lateral stresses due to the operation of the engine. The wall 28 also acts as a step bearing for 45 the valving cylinder. The valving sleeve 13 thus does not take part in guiding the piston in its travel, this function being performed by the cylinder element 7 totally independently of the sleeve 13, whereby the sleeve 13 50 is relieved of the lateral piston pressure due to the angularity of the piston rod or other reasons.

The contacting surfaces of the sleeve 13 and the cylinder walls 8 and 10 may be lubricated in any preferred manner. I have shown a lubricant oil receiving space 29 in which the gears 14 and 15 operate, lubricant being adapted to work its way from this space upwardly to lubricate the sleeve 13. 55 The oil receiving space 29 is constituted in part by the end wall 28 that acts as a step bearing for the valving cylinder and as a positioner for the working or piston cylinder, oil within the space 29 finding passage between the upper surface of the wall

58 and the lower end of the valving cylinder 13 there to lubricate the valving cylinder. Lubricant may be supplied to the space 29 in any suitable way as by means of the pipe 30.

It will be observed that the space within which the sleeve 13 and its operating gearing 14 and 15 work is a lubricant receiving space practically separated from the crank pit, the piston being preferably lubricated 70 by another agency. The valving sleeve 13 being upon the outside of the cylinder is not subject to the initial cylinder heat and the transfer of heat from the cylinder is further opposed by the water intervening in the 75 water jacketing space between the cylinder walls 7 and 8, though I do not limit myself to the presence of the water compartment between the cylinder 7 and the sleeve 13. The sleeve 13 is further cooled by the water 80 in the water jacketing space between the cylinder walls 10 and 11 to which latter water jacketing space I do not wish to be limited. The water jacketing spaces surrounding and surrounded by the sleeve 13 85 are shown as being substantially co-extensive with the sleeve 13, to which characteristic the invention is not to be limited. While the valving and working cylinders of the engine are shown as being co-axial they are 90 not to be limited to this relationship.

While I have herein shown and particularly described the preferred embodiment of my invention I do not wish to be limited to the precise details of construction shown as 100 changes may readily be made without departing from the spirit of the invention, but

Having thus described my invention I claim as new and desire to secure by Letters Patent the following:—

1. An internal combustion plural cycle engine including a working cylinder having intake and exhaust passages; a valving cylinder surrounding the working cylinder; an engine casing; an end wall carried by the 110 engine casing and interposed between the valving cylinder and crank portion of the engine, this end wall engaging the working cylinder to maintain it in fixed alignment; a lubricant containing space partially 115 formed by said end wall; and gearing for turning the valving cylinder, the working space of the gearing being in communication with the lubricant containing space where- 120 by said gearing is lubricated.

2. An internal combustion plural cycle engine including a working cylinder having intake and exhaust passages; a valving cylinder surrounding the working cylinder; and gearing adjacent the crank end of the 125 valving cylinder for turning the valving cylinder, there being a lubricant containing space in communication with the gearing space to enable the lubrication of the gearing.

3. An internal combustion plural cycle en-

gine including a working cylinder having intake and exhaust passages; a valving cylinder surrounding the working cylinder; an engine casing; and an end wall carried by the engine casing and interposed between the valving cylinder and crank portion of the engine, this end wall engaging the working cylinder to maintain it in fixed alignment.

In witness whereof, I hereunto subscribe my name this twenty second day of January A. D., 1913.

PERCY WARREN NOBLE.
